INVENTOR.
HERMAN H. HELLAND

BY
Irving S. & Catharine
ATTORNEYS.

UNITED STATES PATENT OFFICE

HERMAN H. HELLAND, OF FARGO, NORTH DAKOTA

DOOR REGISTER

Application filed November 9, 1929. Serial No. 405,981.

This invention appertains to pads and holders therefor and one of the primary objects of my invention is to provide a device for registers and the like adapted to be located above the door bell for permitting callers to make notations of their visits, should no one be at home on the premises.

Another important object of my invention is the provision of a novel case containing a pad and pencil, the case being adapted to be secured to the door frame above the door bell and having a swinging door or closure, which, when in its open position will form an efficient rest or desk top for permitting the making of desired notations on the pad.

A further salient object of my invention is the provision of novel means for detachably associating the pad with the hinged door of the case, whereby a new pad can be readily associated with the case when the first pad has been used up, the pad being provided with perforated leaves to facilitate the carrying out of used leaves.

A further important object of my invention is the provision of novel means for associating a pencil or similar writing implement with the case, the pencil forming one embodiment of the invention the locking means for holding the closure in its raised position.

A still further object of my invention is to provide an improved door register for residences and the like which is of an exceptionally simple and durable character, and which can be manufactured and placed upon the market at a small cost and readily associated with a door frame by the ordinary layman.

With these and other objects in view, the invention consists in the novel construction, arrangement and formation of parts, as will be hereinafter more specifically described, claimed and illustrated in the accompanying drawings, in which drawings:—

Figure 1 is a front elevation of my improved door register showing the same in position on a door frame above the door bell.

Figure 2 is a side elevation of my improved device showing the same in its operative position on a door frame.

Figure 3 is a transverse section through the improved device taken on the line 3—3 of Figure 1 looking in the direction of the arrows.

Figure 4 is a vertical central section taken centrally through the device on the line 4—4 of Figure 1 looking in the direction of the arrows.

Figure 5 is a section similar to Figure 4 showing the hinged closure in its lowered position forming a rest for the writing pad to permit notations to be made thereon.

Figure 6 is a fragmentary detail perspective view illustrating the means for receiving the pencil and for permitting the pencil to act as a locking bar for the case.

Figure 7 is a horizontal sectional view taken on the line 7—7 of Figure 5 showing the door or closure in its lowered position forming the rest or desk top.

Figure 8 is a detail sectional view through the cover or closure taken on the line 8—8 of Figure 7.

Figure 9 is a detail view of the closure looking from the inside thereof showing the pad removed and the bar for detachably receiving the pad.

Figure 10 is a detail perspective view of the pad.

Figure 11 is a fragmentary front view of a modified form of the invention.

Figure 12 is a sectional view on the line 12—12 of Figure 11.

Figure 13 is a view similar to Figure 12 showing the closure in its lowered open position.

Referring to the drawings in detail, where in similar reference characters designate corresponding parts throughout the several views, the letter A generally indicates my improved device which is adapted to be secured to a door frame above or adjacent to the door bell B of a residence.

My improved device A comprises an open frame plate 15 preferably stamped from sheet metal of the desired gage. This frame plate includes substantially flat upper and lower end bars 16 and 17, and side bars 18 and 19. The inner edges of the side bars 18 and 19 have struck outwardly therefrom the

right angularly extending guide flanges or side walls 20 which act as side walls for the case, as will be later described.

The upper and lower end bars 16 and 17 are provided with suitable openings for the reception of fastening screws 21 or the like whereby the frame plate may be secured to the door frame or other convenient point adjacent to the door bell.

10 The device A also includes a hinge cover or lid 22 which is also preferably stamped from sheet metal and the same includes a flat front wall 23, top and bottom walls 24 and 25 and the side walls 26 and 27. These walls 15 24, 25, 26 and 27 all extend inwardly from the front flat walls 23 and are adapted to extend over the side walls or flanges 20 of the frame plate 15 when the cover is in its raised closed position. A hinge pin or rod 28 is extended 20 through the side walls 26 and 27 of the cover and through the side walls or flanges 20 of the frame plate. By this arrangement the cover 22 can be swung to a lowered position and the front wall 23 will abut the lower 25 edges of the flanges or side walls 20 of the frame plate which will hold the cover in a substantially horizontal position to permit the same to be used as a rest or desk top, for a purpose, which will be later described.

30 The upper wall 24 of the hinged cover 22 can be provided with the upwardly and outwardly extending lips 29 which forms a finger grip to facilitate the raising and lowering of the cover.

35 The cover is adapted to receive and hold a writing pad 30 and this pad is of such a size as to be entirely inclosed by the case when the cover is in its raised position.

The pad or tablet 30 preferably includes 40 a cardboard back 31, and a plurality of leaves 32 bound together by a binding strip 33 at one end. The leaves 32 adjacent to the binding strip 33 are preferably perforated as at 34 so as to facilitate tearing off the leaves 45 of the pad adjacent to the binding strip.

In order to hold the pad on the cover in proper position, the cover is provided with a locking strip or bar 35 which strip extends through suitable openings 36 formed in the 50 side walls 26 and 27 adjacent to the front wall 23 thereof. This locking strip 35 is preferably bent slightly at an angle as at 37 at one end and the other end is provided with a right angularly extending locking tongue 38 55 so as to prevent the accidental displacement of the locking bar from the cover. If desired, this locking bar at a point spaced from the tongue 38 can be provided with a shoulder 39 for engaging the inner edge of the 60 side wall 27.

By this arrangement, it can be seen that the tablet or pad 30 can be slipped into the cover 22 over the locking bar 35 so that the back 31 of the pad or tablet will lie under 65 the locking bar.

By this arrangement the tablet or pad can be readily removed and new pads inserted when the occasion arises.

In one form of my invention, as shown in Figures 1 to 7 inclusive, the side bar 19 of the frame is provided with outwardly extending spaced barrels 40 and 41 which are of such a diameter as to snugly receive a writing pencil 42 therein. The side walls 27 of the swinging cover 22 can likewise be provided with a laterally extending substantially arcuate locking bar 43 which is adapted to extend between the barrels 40 and 41 when the cover is in a raised position. When the cover is in its raised position and the pencil is inserted in the barrels 40 and 41 the pencil will lie in front of the locking bar 43 and thereby prevent the accidental swinging down of the cover. This forms not only an efficient means for holding the pencil but also as an effective means for holding the hinge cover in its closed position. One upper corner of the frame plate 15 can be provided with a suitable opening 44 through which can be threaded a cord for connection with the pencil 42 so as to prevent accidental loss or displacement of the pencil.

In Figures 11 to 13 inclusive, I have shown a slightly modified form of the invention in which the holder for the pencil and the lock is eliminated and in this form, in order to hold the cover in its raised closed position I can employ a coil spring 50 which can be placed around the hinge rod 28. One end of the spring can be bent and hooked over the side wall 20 of the frame plate 15, while the opposite end of the spring can be bent and hooked over the front wall 23 of the cover 22, as at 52.

Thus this spring will function to normally hold and move the cover to a raised position after the same has been swung down for writing purposes.

From the foregoing description, it can be seen that I have provided an effective means for connection with the door frame of a residence for permitting persons to make notations of their visit should no one be at home at the time of the call.

The outer face of the cover 22 can be utilized for advertising purposes or other suitable indicia can be placed thereon, such as the name of the persons living in the house and the use to which the register can be placed.

Changes in details may be made without departing from the spirit or the scope of the invention, but:—

What I claim as new is:

1. A device for permitting callers to make 125 notations of their unanswered visits at the place of their visits comprising a frame plate having struck out side walls, means for connecting the frame plate with a door frame, a hinge cover comprising a front wall and in- 130

- wardly extending top, bottom, and side walls for receiving the struck out walls of the frame plate, a hinge pin extending through the side walls of the cover and the walls of the
- 5 frame plate, a writing pad detachably connected with the inner face of the cover and arranged in the plane of the walls of said cover, and a manipulating thumb piece carried by the upper end of the cover.
- 10 2. A device for permitting callers to make notations of their unanswered visits at the place of their visits comprising a frame plate having struck out side walls, means for connecting the frame plate with a door frame, a
- 15 hinge cover comprising a front wall and inwardly extending top, bottom, and side walls for receiving the struck out walls of the frame plate, a hinge pin extending through the side walls of the cover and the walls of the
- 20 frame plate, a writing pad detachably connected with the inner face of the cover and arranged in a plane of the walls of said cover, a manipulating thumb piece carried by the upper end of the cover, a pair of spaced barrels carried by and projecting forwardly from the frame plate, a locking bar carried by the cover and adapted to ride between the barrels when the cover is in a raised position, and a pencil removably received in said
- 25 barrels and lying in front of the locking bar when the cover is in its raised position whereby accidental downward movement of the cover is prevented.
3. A device for permitting callers to make
- 30 notations of their unanswered visits at the place of their visits comprising a frame plate having struck out side walls, means for connecting the frame plate with a door frame, a hinge cover comprising a front wall and inwardly extending top, bottom, and side walls for receiving the struck out walls of the frame plate, a hinge pin extending through the side walls of the cover and the walls of the
- 35 frame plate, a writing pad detachably connected with the inner face of the cover and arranged in the plane of the walls of the cover, a manipulating thumb piece carried by the upper end of the cover, and a coil
- 40 spring about said pivot rod having its opposite ends engaging respectively the frame plate and the cover.

In testimony whereof I affix my signature.

HERMAN H. HELLAND.
